UNITED STATES PATENT OFFICE.

LOTHAR R. ZIFFERER, OF COLUMBIA, PENNSYLVANIA.

CONCRETE INSERT.

Application filed June 18, 1927. Serial No. 199,707.

This invention relates to a concrete insert with which is associated an adjustable fastening means. For its objects my invention aims to provide a device of this character which is strong, simple, and easily produced; and one wherein the adjustable fastening means is thoroughly protected during the concrete pouring operation which secures the insert in place.

10 A suggestive embodiment of my invention is set forth in the accompanying drawing wherein—

Figure 1 is a vertical section through the insert in its entirety shown in position adjacent form boards prior to their being removed from the concrete casting;

Fig. 2 is a bottom plan view of the insert;

Fig. 3 is a transverse section therethrough taken on line 3—3 of Fig. 2; and

20 Fig. 4 is a central vertical section through the insert and surrounding concrete casting, showing a supporting device attached thereto.

The present insert may consist of a metal casting formed to provide a top or back wall 5 from which depend side and end walls 6 and 7, respectively. Extending inwardly from these latter walls are flanges 8 which define between them an elongated slot 9. Between the flanges and the back wall 5 is a 25 chamber 10 wherein is confined a nut 11 which is freely slideable for the length of the chamber.

The end walls may be extended upwardly and divergently to provide legs 12 which terminate in feet 14, reinforcing ribs 15 adding thereto a desired strength. In addition, I provide bifurcated lugs 16 outwardly extended in opposite directions from the side walls 6, and preferably flush with the flanges 8 thereof. A marginal rib 17 extends around the insert lower or front face which is formed by the flanges 8.

During installation the insert is arranged adjacent form boards 18, as shown in Fig. 1, with its ribs 17 sunk into the form sufficiently to provide a seal against the seepage of water or loose material when the concrete is poured.

In this manner, the chamber 10 wherein the nut is confined is effectively protected. By the use of nails or other equivalent devices 50 driven into the form board through the lugs 16, the insert may be accurately centered in its intended position.

It will be apparent that the insert so provided will be firmly anchored after the concrete has set. Upon removal of the form boards 19 may be threaded into the nut for attachment thereto. This bolt may have connection with any desired object, such as a hanger 20 supporting a pipe 21. When so supported, a limited adjustment of the nut is provided for due to its sliding mounting within the insert chamber. In any selected position of adjustment the nut may be locked by turning the bolt sufficiently to present its end with pressure against the top or back wall 5 of the insert.

The structure just described is almost wholly concealed when placed in use. Only a small portion of one face remains visible, 70 and this is surrounded by the marginal flange 17 which defines in effect a panel that is pleasing to the eye.

I claim:

A concrete insert hollowed to provide a 75 chamber which is enclosed on all sides except the front face thereof wherein is formed an elongated slot, a nut slidably disposed within the chamber having a threaded aperture in alignment with the elongated slot in all ad- 80 justed positions of the nut, a bolt having a screw-threaded connection with the nut and extended therefrom through the slot and a marginal depending sealing rib extending around the front face of the insert and adapted to be embedded in a form board wherein the insert is secured prior to moulding of a body of concrete theraround, the marginal rib defining on said insert front face a panel 85 which projects below the body of concrete and is exposed to view upon removal of the form, substantially as described.

LOTHAR R. ZIFFERER.
